MULTIPLE FLANGED FIN FOR HEAT EX- CHANGERS AND METHOD OF PRODUC- ING INDIVIDUAL FINS

Benjamin Spieth, Racine, Wis., assignor to Modine
Manufacturing Company, Racine, Wis., a cor-
poration of Wisconsin

Application October 24, 1947, Serial No. 781,823

3 Claims. (Cl. 113—118)

1

This invention relates to a multiple length fin for heat exchangers and the method of making fins, and its principal object is to permit of quantity production of units and of assemblies, with a considerable saving of time. The heat exchange element of many types of apparatus; for example, a convector as used for home heating, requires a considerable number of relatively short fins. These fins are ordinarily in the range of 3½ inches to 10 inches long. In modern shop practice, only one fin would be made at each stroke of a press. Such an operation in itself is relatively slow, and hence, costly. Furthermore, it is probable that these individual fins must be handled singly in subsequent assembly operations, and such an operation is costly where thousands of parts are to be assembled.

I propose to make a multiple length fin, each multiple length, say 26 inches to 36 inches long. Each multiple length fin is produced at each stroke of a punch press. Thus, there is a considerable saving in strokes, with resultant saving in time, when producing a given number of completer units. Likewise, experience shows that multiple length fins can be assembled with tubes consuming but little more time than a single length fin.

To accomplish the desired objects, I have designed a multiple length fin which may be readily formed, be readily handled and assembled into multiple assemblies, the multiple assemblies processed as a unit, and a feature of the design wherein the multiple assembly can be readily and accurately parted into the final units of desired width. Provisions are incorporated in the design so that after the multiple assembly has been parted into unit assemblies, there are provisions for readily attaching side plates, or side guards. The details of this means for attachment, and the design of the side plates is the subject of my copending application, Serial No. 776,363, filed September 26, 1947, for patent on Heating Element for Convection Heaters, now Patent No. 2,545,561, issued March 20, 1951.

With these and other objects and advantages in view, this invention consists in the several novel features of construction herein described, and in the herein described method of making fins as more particularly defined in the appended claims.

The invention is clearly illustrated in the accompanying drawing, in which:

Fig. 1 is a side elevation partly broken away of a multiple length fin embodying a simple form of the present invention;

Fig. 2 is a detail vertical section taken on the line 2—2 of Fig. 1;

Fig. 3 is a fragmental detail horizontal section taken on the line 3—3 of Fig. 1;

Fig. 4 is a perspective view of a fragment of one of the individual fins;

2

Fig. 5 is a view partly in vertical cross section and partly in elevation of a side plate and fragment of a fin of a heat exchanger core, and

Fig. 6 is a detail horizontal section taken on the line 6—6 of Fig. 5.

Figures 2 to 6 are upon an enlarged scale.

Referring to said drawing, the reference character 10 designates a multiple length fin from which a number of individual fins are to be parted.

The multiple length fin is given its shape with suitable dies in a punch press at one operation. Flanged holes 11, 12 are struck up with suitable dies at suitable spaces. Individual fins, made from multiple length fins, may have two or more holes as the case may be, and in the drawing the sections which comprise the individual fins each have three holes 11 or 12 as illustrated.

At the ends of each section which define the ends of the individual fins, the metal is slit at the edge portions and intermediate the edge portions and struck up to form flanges 13, 14 arranged in aligned pairs with a blank space between the flanges of each pair. Between the pairs of flanges, the metal is struck up with suitable dies to provide aligned beads 15 preferably of concavo-convex form with their crowns disposed midway between the planes of the flanges of each pair.

For stiffening the individual fins, concavo-convex beads 16, 16, that run lengthwise of the multiple length fin adjacent the edges thereof are struck up with suitable dies.

The punch press upon which the multiple length fin is blanked up may have retractile punches which strike up the flanges 13, 14 and beads 15, and only those punches which are to be used in striking up said flanges and beads at the ends of sections which comprise the individual fins are set into operative position. Those flanges 13, 14 and beads 15 which are illustrated in solid lines in Fig. 1 indicate the flanges and beads of each individual fin section, wherein three holes 11 are provided in each individual fin.

If the individual fins are to contain two holes 11, the punches are set to strike up the flanges and beads indicated at a, b; if the individual fins are to contain four holes, the punches are set to strike up the flanges and beads indicated at b, and after each subsequent group of four holes,

and if the individual fins are to contain five holes, the punches are set to strike up the flanges and beads at c, and after each subsequent group of five holes. Thus, the punches for any given predetermined length of fin may be set into operative position to strike up the flanges and beads at the ends of each individual fin section.

After a great number of multiple length fins have been struck up, the multiple fins are assembled on to tubes, usually several fins per inch as conditions demand, by any suitable means and

thus produce a multiple slab comprised of tubes and fins. Any processing required to attach the tubes to the fins in a heat conduction oven may be made at this stage. However, the particular design described anticipates that the fins be attached to the tubes with solder, also, that the side plates be attached to the flanges with solder. Modern production techniques would then require that the fin stock have a coating of solder before the fins are formed in dies.

When the multiple slab has been completed as far as possible, it may be divided into units by a band saw. Experience proves that a band saw directed into the bottom of the formed beads will be constrained to remain in the bottom of the bead, until the fin is parted. This action continues as the saw blade severs the individual fins in quick succession through the length of the slab assembly. Thus, the design provides means for quickly, economically and accurately separating the slab assembly into individual units.

The sawing of the slab is repeated at each division point and the end pieces 16 are sawed off and become waste. Thus, each multiple length fin is divided into a plurality of individual fins indicated by 10a in Figs. 4, 5 and 6.

In making up individual cores, side plates 17 (see Figs. 5 and 6) are soldered or brazed to the flanges 13, 14 of the fins of the core. The flanges provide relatively wide faces for soldering or brazing purposes. The flanges, although primarily intended as a means for attaching the side plates, assist to a considerable degree in holding the saw in its proper position during the sawing operation.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. In a multiple length flanged fin for heat exchangers, the combination of an elongated metal fin strip having a plurality of longitudinally spaced rows of openings therein, each row extending transversely across the strip, the openings of each row being transversely spaced and defining the juncture of adjacent individual fin sections, with the material between the respective openings of each row forming a plurality of connecting strips between adjacent fin sections operative to retain the latter in a single multiple strip, the connecting strips of each row being formed in the shape of concavo-convex beads and adapted to be severed thereat to form individual fin sections, the beads of each respective row being aligned, the corresponding face of each fin section having flanges extending outwardly therefrom and transversely to the plane of such fin section, said flanges forming the transverse edges of the respective openings and being formed from metal originally occupying the area of the respective openings therebetween, said edges extending parallel to one another, and each fin section having one or more tube receiving holes therein.

2. In a multiple length flanged fin for heat exchangers, the combination of an elongated metal fin strip having a plurality of longitudinally spaced rows of elongated openings therein, each row extending transversely across the strip,

the openings of each row being transversely spaced with the long axis of such openings being in alignment and defining the juncture of adjacent individual fin sections, with the material between the adjacent ends of the respective openings of each row forming a plurality of connecting strips between adjacent fin sections operative to retain the latter in a single multiple strip, each fin section having flanges extending transversely to the plane thereof and forming the transverse edges of the respective openings, with the flanges on adjacent fin sections lying in parallel planes, said flanges being formed from portions of the metal originally occupying the area of the opening therebetween, said connecting strips being deformed out of the plane of said fin sections to provide a concavo-convex bead adapted to guide a severing tool between said flanges, and each fin section having one or more tube receiving holes therein.

3. The method of producing individual flanged fin sections, which comprises the steps: forming tube receiving holes in a rectangular multiple length fin strip, severing longitudinally adjacent portions of said strip and bending the same outwardly from the plane of said strip to form a plurality of longitudinally spaced rows of aligned transversely spaced openings in said sheet, adjacent rows of openings defining the length of individual fin sections, with the longitudinally opposite edges of each opening being defined by oppositely disposed rectangular flanges formed from portions of the material originally occupying the area of the opening therebetween and lying in planes extending substantially perpendicularly to the plane of said strip with said fin sections connected to one another at a plurality of points by the remaining material extending between adjacent openings to maintain said strip as a unitary structure, forming the material between adjacent openings into concavo-convex beads and subsequently sawing said beads formed from said connecting material with a severing tool, without disturbing the respective adjacent flanges, to sever the flanged individual fin sections from one another.

BENJAMIN SPIETH.
